UNITED STATES PATENT OFFICE.

JOHN O. MADISON, OF BROOKLYN, NEW YORK.

TRUSSSED-SHEET BUILDING MATERIAL.

1,277,622.

Specification of Letters Patent.

Patented Sept. 3, 1918.

Application filed June 30, 1916. Serial No. 106,823.

To all whom it may concern:

Be it known that I, JOHN O. MADISON, a citizen of the United States, residing at Brooklyn, in the county of Kings and State 5 of New York, have invented a certain new and useful Improvement in Trussed-Sheet Building Material, of which improvement the following is a specification.

This invention relates to building material for walls, partitions, flooring, ceilings, roofs, and the like, and has for its object to provide an improved truss sheet construction which shall be fire-proof, heat-insulating, sound proof, and of light weight, 10 but at the same time shall be strong and durable, and adapted to carry heavy loads.

My invention comprises, primarily, a pair of sheets, preferably steel, constituting the outer chord members of the trussed structure, and rigidly connected together at certain intervals by intermediate web members composed of integral projections or depressions formed on one or both sheets and separated from each other laterally and longitudinally, preferably in a staggered relation, said projections or depressions being of a depth many times the thickness of the sheet sufficient to produce a strong truss effect, and formed integral with the sheet by 25 means of a rolling, molding or pressing process, in which case the depressions will be of such a depth as is consistent with the practice in the art of deep pressing, drawing, or metal rolling, as well as with the 30 economical distribution of the material for trussing purposes, whereby the sheets are spaced apart and rigidly secured together in a trussed relation, which forms a very light but strong and durable construction, 35 capable of sustaining heavy loads. The trussed sheet structure may also be covered, on one or both sides, with a layer of concrete, cement or other plastic, stiffening, insulating, or wearing material, securely fastened to said sheet or sheets.

In the accompanying drawings: Figure 1 is a sectional view, showing one form of trussed sheet metal construction embodying my improvement; Fig. 2, a similar view 40 showing a modified construction; Fig. 3, a similar sectional view showing the plastic material applied to one side of the trussed metal sheet; Fig. 4, a plan of the form of trussed metal sheet shown in Fig. 2; Fig. 5, 45 a sectional view showing one method of anchoring or securing the layer of cement

or plastic material to the metal sheet; Fig. 6, an inverted plan of same; Fig. 7, a sectional view similar to Fig. 3, but showing layers of plastic material secured upon both 50 sides of the trussed metal sheets; and Fig. 8, a plan, similar to Fig. 4, but showing a different shape of depressions or truss members.

According to the construction shown, my 55 improvement comprises a pair of metal plates constituting outer chord members of the trussed structure and spaced apart in a substantially parallel relation by intermediate web members rigidly connected with 60 said plates. The web of the truss members are preferably formed of integral portions of one or both of said plates or sheets in the form of deep depressions, which may be pressed or rolled into the metal sheet at 65 certain spaced intervals. This spacing interval of the depressions in the direction of stress, preferably has a certain relation to the thickness of the compression chord member of the truss, being a certain number 70 of times this dimension in order to prevent undue buckling of the sheet. As shown in Fig. 1, one of the metal sheets, 13, is provided with the integrally connected depressions, 15, while the other metal sheet, 14, 75 is a plain sheet rigidly secured to the said depressions by riveting or by a spot weld at the bottom or apex of each depression, or in any other convenient way.

A preferred construction is shown in 80 Fig. 2, in which the two metal sheets, 13 and 13^a, are of the same form and construction, both having the regularly spaced depressions, 15, which are placed back to back and rigidly secured together at the bottom 85 or apices of said depressions. In this way the two plates are spaced apart a distance substantially equal to double the depth of the depressions and form a strong and durable sheet metal structure for use in building 90 structures of various kinds, such as flooring, walls, partitions, roofs, etc.

When used as flooring, one or both sides of the sheet metal structure may preferably be provided with a layer of plastic or insulating material, 16, such as cement or concrete and the same may be rigidly anchored or secured to the metal sheets in any desired manner, as for instance by metal clips, 17, welded into some of the cup shaped depressions, 15, as indicated in Figs. 3 and 7. A preferred means, however, for fastening

the layer or layers of insulating plastic material to the metal sheets is shown in Figs. 5 and 6, wherein some of the depressions, 15, are pressed inward at opposite 5 sides to form openings, 18, through the metal sheet to permit the plastic material to force itself through to some extent when soft, and then to securely anchor itself in position when the same hardens, as will be 10 readily understood. Except for these small openings for the plastic material the sheet is preferably formed substantially whole or imperforate in order to increase the strength and stiffness of the trussed structure.

15 For strengthening purposes, the metal sheets may be provided with strengthening ribs, 19, arranged either longitudinally, diagonally, or both, as indicated in Fig. 4. The depressions may also be made elongated or otherwise varied in shape to suit 20 different conditions as shown in Fig. 8.

The space between the two metal sheets may be filled with mineral wool, felt, or other sound deadening or a heat insulating 25 material, or may be left clear, the air space itself constituting an excellent heat insulating medium. This space may also be used for currents of air or other fluid for ventilation, heating, or refrigeration purposes, 30 or the space may be made tight by sealing at the edges and thereby serve to increase the buoyancy when the material is used in the construction of floats, life boats, rafts, ships, aeroplanes, seaplanes, hydroplanes, 35 submarines, etc.; as for example, when the construction is of aluminum or its alloys, the buoyancy is several times greater than that of wood construction.

An essential feature of my improvement 40 comprises the construction in which the sheet having the projections or depressions forming the web members, itself constitutes a chord member of the trussed structure, and where the depressions are formed in 45 both sheets, these constitute the two opposite outer chord members, whereby a two-sheet construction is produced in which the material of the sheets is located as far as possible from the middle or neutral axis, 50 and consequently gives a maximum resistance to the bending and shearing stresses, and the most economical distribution of the material for a given weight and depth of the trussed structure. At the same time 55 when sealed at the edges this construction gives a greatly increased displacement and buoyancy. The chord members may, of course, be increased in thickness with additional sheets if desired.

60 While the preferred construction, as herein described, applies to a metal sheet structure, it will be evident that there may be certain instances wherein sheets of strong non-metallic material may be used for producing a very serviceable and durable 65

trussed structure, and my invention is not therefore limited to metal sheets only, but may also cover sheets of certain non-metallic material that may be compressed or molded into the desired shape.

I am aware that, prior to my invention, panel structures have been proposed, in which two outer plain metal sheets have been spaced apart and secured by an intermediate reinforcing sheet or sheets having 70 projections or depressions formed thereon, but in no case, so far as I am aware, do such prior structures disclose a sheet provided with the above described integral projections or depressions, and itself constituting 75 an outer or chord member of the trussed structure. This is an important feature of my improvement, since by this means a scientifically constructed and highly efficient trussed structure may be produced by using 80 two sheets only, whereas in said prior constructions it is necessary to employ three or more sheets.

Having now described my invention, what I claim as new and desire to secure by Letters Patent is:

1. A trussed sheet structure adapted to withstand heavy loads or stresses, comprising a continuous rigid sheet constituting a chord member of the truss, and formed 95 with permanent integral depressions of a depth many times the thickness of the sheet, sufficient to produce a strong trussing effect, said depressions forming web members spaced apart laterally and longitudinally 100 suitable distances to prevent buckling, and another sheet rigidly secured to the apices of said depressions and constituting an opposite chord member of the trussed structure.

2. A trussed sheet structure, comprising a metal sheet constituting a chord member of the truss, and formed with permanent integral depressions of a depth many times the thickness of the sheet, sufficient to produce 110 a strong trussing effect, said depressions being suitably spaced laterally and longitudinally in a staggered relation and constituting the web members, and another metal sheet rigidly secured to the apices of 115 said depressions and constituting an opposite chord member of the truss.

3. A trussed sheet structure, comprising a metal sheet constituting a chord member of the truss, and formed with permanent elongated depressions of a depth many times the thickness of the sheet sufficient to produce a strong trussing effect, said depressions forming web members spaced apart laterally and longitudinally distances suitable to prevent 125 buckling, and another metal sheet rigidly secured to the apices of said depressions and constituting an opposite chord member of the trussed structure.

4. A trussed sheet structure, comprising a 130

- metal sheet constituting a chord member of the truss, and formed with permanent integral projections of a depth many times the thickness of the sheet, sufficient to provide a 5 strong trussing effect, said depressions forming web members spaced apart laterally and longitudinally distances suitable to prevent buckling, and another metal sheet having corresponding depressions rigidly secured to the apices of the depressions of the first sheet.
5. A trussed sheet structure, comprising two metal sheets constituting the opposite chord members of the truss, and each formed 15 with permanent integral depressions of a depth many times the thickness of the sheet, sufficient to provide a strong trussing effect, said depressions being suitably spaced laterally and longitudinally in a staggered relation and rigidly secured together at the inner ends or apices of said depressions to constitute the web members of the truss.
6. A trussed sheet structure adapted to withstand heavy loads or stresses, comprising 25 a sheet constituting a chord member of the truss, and formed with permanent integral depressions of a depth many times the thickness of the sheets, sufficient to produce a strong trussing effect, said depressions forming web members spaced apart laterally and longitudinally suitable distances to prevent buckling, another sheet rigidly secured to the apices of said depressions and constituting an opposite chord member of 30 the trussed structure, a layer of plastic ma-

terial applied to said first sheet and filling said depressions, and means for anchoring the plastic material to said sheet.

7. A trussed sheet structure adapted to withstand heavy loads or stresses, comprising 40 a sheet constituting a chord member of the truss, and formed with permanent integral depressions of a depth many times the thickness of the sheets, sufficient to produce a strong trussing effect, said depressions 45 forming web members spaced apart laterally and longitudinally suitable distances to prevent buckling, another sheet rigidly secured to the apices of said depressions and constituting an opposite chord member of 50 the trussed structure, and a layer of plastic material applied to said first sheet and filling said depressions, some of the depressions being perforated to allow the plastic material to anchor itself to said sheet. 55

8. A trussed sheet structure, comprising a substantially whole or imperforate sheet constituting a chord member of the truss, and formed with permanent integral depressions of a depth many times the thickness of the sheet, sufficient to produce a strong trussing effect, said depressions being suitably spaced laterally and longitudinally to prevent buckling and constituting 60 web members, and another sheet rigidly secured to the apices of said depressions and constituting an opposite chord member of 65 the truss.

JOHN O. MADISON.
